No Drawing. Application June 17, 1938,
 Serial No. 214,344

3 Claims. (Cl. 167—65)

This invention relates to alkyl nitrites having pharmacological and clinical activity and being otherwise suitable for use as therapeutic agents, particularly as vaso dilators.

5 Certain alkyl nitrites such as ethyl nitrite and amyl nitrite are known and have been used as vaso dilators. These lower alkyl nitrites, i. e., nitrites of alkyls having less than six carbon atoms, are quite unstable chemically, uncertain 10 in their physiological action and unpleasant and unsafe to use therapeutically. I have found that they are relatively more toxic and irritating than the higher alkyl nitrites and produce undesired effects on the oxy-hemoglobin when used in ani- 15 mals. On the other hand I have found that alkyl nitrites in which the alkyl group contains more than twelve carbon atoms have practically no vapor pressure and for this reason are not suitable for therapeutic use because they cannot be 20 administered by inhalation.

In the course of my investigation I have found that alkyl nitrites containing from six to twelve carbon atoms in the alkyl group and more especially those containing from six to ten carbon 25 atoms are pharmacologically active and give results of quite a different character from those produced by the lower alkyl nitrites, exemplified by a striking lack of toxicity and absence of detrimental effect on oxy-hemoglobin. The 30 compounds tend to become less active pharmacologically as the number of carbon atoms in the alkyl group increases above eight and, as indicated above, twelve carbon atoms in the alkyl group represents a practical upper limit.

35 The properties of the alkyl nitrites having six to twelve carbon atoms which are believed to be principally responsible for their clinical utility are their low but substantial volatility, their chemical stability and their lipoid solubility. If 40 the compounds were not volatile they could not be administered by inhalation. On the other hand, if the compounds were too volatile they would be too readily and quickly exhaled from the lungs and would have less chance to exert 45 their systemic effects. Moreover high volatility favors high concentration in the blood which is objectionable. Their lipoid solubility insures that they will be removed from the blood stream by absorption into the fatty tissue and lipoid-like substances in the body thereby producing 50 their effects, for example, on the walls of the blood vessels. If they were not soluble in or absorbed by the tissue of the body, they would concentrate in the blood stream and exert their 55 toxic effect and detrimental action on the blood

and they would be lost by exhalation more quickly. Their chemical stability, of course, is associated with their low toxicity. Owing to their low volatility and high lipoid solubility, their sojourn in the blood stream is shortened, their 5 toxicity is reduced and their depressor action is prolonged. Shortening the sojourn of the compounds in the blood stream obviates the formation of toxic by-products such as met-hemoglobin. 10

The compounds embraced by my invention may be represented by the general formula:

in which n is a whole number not less than six 15 nor more than twelve. They are generally characterized as straw colored oily liquids possessing a characteristic odor and a specific gravity somewhat less than that of water. They are chemically stable at atmospheric temperatures but decompose slowly under the influence of direct sunlight presumably liberating nitric oxide. They are very slightly soluble in water, soluble in the common organic solvents and readily soluble in lipoidal material. 20

25 The following example illustrates the preparation of the octyl nitrite:

172 cc. of 2-ethyl hexanol-1 is added to a mixture of 1100 cc. of water and 110 cc. of concentrated hydrochloric acid and cooled at 0° C. 30 A solution of 110 grams of sodium nitrite in 500 cc. of water is added to this mixture drop by drop with mechanical stirring and at such a rate that the temperature is kept below 10° C. After all the solution has been added, stirring 35 is continued until practically all the blue color has disappeared from the lower layer. The two layers are separated and the octyl nitrite is dried with anhydrous sodium sulfate or other suitable drying agents. It is then filtered and distilled 40 under reduced pressure. The boiling is plus or minus 55° C. at 8-10 mm. Analysis of the finished product from several batches has shown it to vary from 94% to 96% octyl nitrite.

45 The nitrites of other alkyls may be similarly prepared.

The properties of the compounds have been determined by pharmacological and clinical tests. Their effect on coronary vessels has been determined by (1) perfusion of the coronary vessels 50 of the isolated rabbit's heart (2) use of the coronary rings of the steer and (3) the Moravitz and Zahn experiment on the dog in situ. By these methods various compounds were compared and their degree of prolonged depressor 55

activity and the rapidity of the return of the subjects to normal was ascertained.

In addition, the acute toxicity by inhalation and injection was determined using white male 5 rats. Subacute toxicity was also determined by both of these methods on rats. Furthermore, the effect upon hemoglobin was studied in the living animal. All of these experiments with nitrites of the group defined above, and particularly octyl 10 nitrite, have demonstrated their unusual pharmacological properties. I have proved that they possess the properties of rapid and prolonged action coupled with low toxicity. I have found, furthermore, that they produce no deleterious 15 action on the blood and do not form met-hemoglobin as do alkyl nitrites of low molecular weight. Experimental observation with human subjects has demonstrated that duration of the

depressor response produced by these compounds, particularly octyl nitrite, is six to seven times that obtained with amyl nitrite, even though much smaller doses are used. Clinical experimentation by others has proved that these compounds are useful in conditions where depressor activity or lowering of the blood pressure is indicated, such as asthma, angina pectoris paroxysmal hypertension, or other spasms associated with the constriction of blood vessels. I have 10 found that the most suitable method of application of these compounds is by inhalation.

I claim:

1. A vasodilator comprising an alkyl nitrite of the formula $C_8H_{17}NO_2$.
2. A vasodilator comprising octyl nitrite.
3. A vasodilator comprising ethyl hexyl nitrite.
